S. BERNSTEIN

INSECT POWDER GUN

Filed July 26, 1922

Fig. 1.

Fig. 2.

Fig. 3.

Inventor:
Samuel Bernstein,

By Frederick V. Winters,

Attest.

UNITED STATES PATENT OFFICE.

SAMUEL BERNSTEIN, OF NEW YORK, N. Y.

INSECT-POWDER GUN.

Application filed July 26, 1922. Serial No. 577,554.

To all whom it may concern:

Be it known that I, SAMUEL BERNSTEIN, a citizen of the United States, and resident of New York, in the county and State of New York, have invented certain new and useful Improvements in Insect-Powder Guns, of which the following is a full, clear, and exact specification.

This invention relates to powder guns designed for discharging insect powder, and it has for its object to provide an improved device of this kind having a powder-containing body, a nozzle at one end of said body through which the powder is discharged, and a bellows attached to the other end of the body and having means for preventing the powder from entering and filling up said bellows. Another object is to provide means for preventing clogging at the nozzle and insuring the breaking up and even feeding of said powder to said nozzle.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a central longitudinal section through a powder gun made substantially in accordance with this invention.

Figure 2 is a similar view, showing powder in the container and the positions of the parts when the bellows bulb is compressed and a portion of the powder discharged, and

Figure 3 is a transverse section on the line III—III of Figure 2.

The powder container 1 may be generally tubular in form with the walls at one end thereof tapered at 2 leading to the discharge nozzle 3 which may be closed by a plug 4 when the device is not in use. The other end of the container is closed by a perforated disk 5 over which a bellows bulb 6 is secured in any suitable manner, as by the union 7.

Said bulb 6 has a central air-discharging passage or opening 8, and around said passage or opening there is a flexible valve member or flange 9 which normally covers and closes the perforations 10 in the disk 5, see Figure 1. The central portion of the

disk 5 is imperforate, as shown best in Figure 3, so that when the gun is not in use the valve portion 9 prevents powder from passing into the bulb from the container 1, whereby said bulb always has its maximum contents of air to be forced into said container for discharging the powder therefrom.

When the bulb is compressed, as shown in Figure 2, the air discharged therefrom raises the valve flange 9 away from the perforations in the disk 5, thus allowing said air to enter the container and act upon the powder therein to eject it through the nozzle 3 at the other end of said container. As soon as the pressure is relieved from the bulb the valve flange 9 returns to its normal position shown in Figure 1 where it closes the perforations in the disk 5 and prevents the powder from being sucked back into the bulb from the container. The bulb may be provided with an ordinary relief valve 11 to permit it to fill with air directly from the outside atmosphere instead of through the container.

To prevent the nozzle 3 from becoming clogged with powder so as to interfere with the proper discharge thereof from the container 1, a perforated disk 12 is fitted in said container at the inner end of the tapered passage 2 which leads to said nozzle. The central portion of said disk 12 is imperforate so that the powder will not be forced directly into the nozzle but will pass through the perforations 13 around the marginal portion of said disk and be directed to the nozzle by the tapered walls 2.

I claim:—

1. The combination with a powder container having a nozzle at one end, of a perforated closure for the other end of said container, and a bellows bulb having a portion normally covering the perforations in said closure and cutting off communication between the interiors of the container and bulb for the purpose specified.

2. The combination with a powder container having a nozzle at one end, of a perforated closure for the other end of said container, and a bellows bulb having a flange at its inner end overlapping and normally closing the perforations in said closure for the purpose specified.

3. The combination with a powder container having a nozzle at one end, of a bel-

lows bulb attached to the other end of the container and having a central air-delivery opening, and a closure disk in the container adjacent said bulb, said disk having perforations normally covered by the inner end of the bulb, while the central portion of said disk in line with the air-delivery opening in the bulb is imperforate.

4. The combination with a powder container having a nozzle at one end, of a bellows bulb attached to the other end of the container and having a central air-delivery opening and a flexible valve portion around said opening, and a closure disk in the container adjacent said bulb, said disk having perforations normally covered by said valve portion of the bulb, the central portion of said disk in line with the air-delivery opening in the bulb being imperforate.
5. The combination with a powder container having a nozzle at one end, of a bellows attached to the other end of the con-

tainer, there being a tapered passage in the container leading to said nozzle, and a perforated disk in the container at the inner 25 end of said tapered passage, the central portion of said disk being imperforate for the purpose specified.

6. The combination with a powder container having a nozzle at one end, of a bellows, a flexible valve member connecting the bellows with the other end of the container, and a perforated closure for the latter end of the container, the perforations in said closure being normally covered by said valve 30 35 member for the purpose specified.

7. A compressible bellows bulb of the character described having an integral valve portion extending outwardly around its discharge passage for the purpose specified. 40

In testimony whereof I have signed my name to this specification.

SAMUEL BERNSTEIN.
